VANE TYPE BOOSTER PUMP

Russell R. Curtis, Dayton, Ohio, assignor to
 Curtis Pump Company, Dayton, Ohio, a corporation of Ohio

Application August 7, 1944, Serial No. 548,336

7 Claims. (Cl. 103—118)

This invention relates to a positive-displacement type pump equipped with liquid and vapor-separating means so that only fully liquid material is pumped.

Specifically, the invention deals with a pump and motor unit adapted to be submerged in a pond of volatile liquid material such as gasoline for separating gases and vapors from the gasoline to positively propel only fully liquid gasoline and thereby eliminate vapor lock in the fuel system of an aircraft or other propelled device.

The invention will hereinafter be specifically described as embodied in an aircraft fuel system, but it should be understood that the pumps of this invention have wide usage in separating vapors from liquids and in pumping fully liquid material.

According to the invention an airplane fuel tank, preferably vented to the atmosphere, is provided with an apertured bottom wall. A pump and motor unit has a base mounting plate closing the bottom wall aperture of the tank and supporting the pump and motor unit in the tank. The pump is equipped with an agitator adjacent the bottom of the tank. An open-ended passageway is provided for liquid fuel and the agitator acts on the fuel flowing through this passageway to separate vapors and gases in the fuel from the liquid fuel. Bubbles of gases and vapors are formed which rise freely through the pond out of the passageway. A vane-type pump has an inlet communicating with the passageway. This inlet is covered with a screen which prevents passage of bubbles therethrough. The positive-displacement pump thus only receives agitated liquid from which the vapors have been separated, and propels this liquid to a fuel line. An electric motor drives the rotary vane pump and is carried above the pump from the same base plate.

It is, then, an object of the invention to provide a vane type vapor-separating pump.

Another object of the invention is to provide a booster pump fuel system which agitates the fuel to separate vapors and gases therefrom and which positively propels the fully liquid fuel.

Another object of the invention is to provide a positive-displacement type vapor-separating pump.

A further object of the invention is to provide a pump and motor unit adapted to be submerged in a pond of liquid and having an open-ended annular passageway through which the liquid can freely flow together with an agitator for beating out bubbles of gas and vapor from the liquid in said passageway.

A still further object of the invention is to provide a vane-type pump with an annular vapor-separating chamber and a screened inlet preventing passage of bubbles of gas and vapor therethrough.

Other and further objects of the invention will become apparent to those skilled in the art from the following detailed description of the annexed sheet of drawings, which, by way of preferred example only, illustrates one embodiment of the invention.

On the drawing:

Figure 1 is a fragmentary and broken vertical cross-sectional view, with parts in elevation, of a vane type booster pump according to this invention mounted in a tank.

Figure 2 is a horizontal cross-sectional view, taken along the line II—II of Figure 1.

As shown on the drawing:

20 In Figure 1, the reference numeral 10 designates generally a fuel tank of an airplane containing a pond P of liquid gasoline. The tank 10 has a bottom wall 11 apertured as at 11a.

25 A pump and motor unit 12 is mounted in the tank 10 on a base plate 13 which closes the aperture 11a of the tank bottom wall 11. A mounting ring 14 is seated in the tank 10 on the bottom wall 11 around the aperture 11a thereof and cap screws 15 are passed through the base plate 13 and bottom wall 11 into threaded relation in the mounting ring 14 for securing the pump and motor unit 12 in the tank and for sealing the aperture 11a of the tank. A sealing gasket (not shown) can be interposed between the base plate 30 13 and the tank wall 11.

35 The base plate 13 has an aperture 13a therein closed by a cover or cap 16 which is secured to the plate 13 by means of cap screws 17. A drain plug 18 is provided in the cap 16.

40 The base 13 has an upstanding tubular leg 19 closed at the bottom by means of a cap 20 and receiving a conduit fitting 21 at the top thereof. A single bolt 22 is passed through the cap 20 and threaded into a hub 21a of the conduit fitting and secures the fitting and cap in position. The fitting 21 and cap 20 can be interchanged.

45 The upstanding tubular leg 19 has a horizontal tubular portion 23 projecting therefrom reinforced by a rib 24. An upstanding flange 25 projects upwardly from the end of the tubular portion 23 and is also reinforced by the rib 24. This portion 25 carries a horizontal ring 26 at the upper end thereof on which is mounted a 50 casing head 27 for an electric motor 28. The elec-

tric motor is covered by a casing 29 supported on the head 27. The head 27 has a hollow vertical boss portion 27a carrying a bearing 28a for the motor shaft 30. A stationary seal 31 is mounted in the boss portion 27a and coats with a rotating seal ring 32 driven by the shaft 30.

A gear 33 is secured on the lower end of shaft 30 in meshed relationship with a gear 34 of a pump shaft 35.

The tubular portion 23 carries a vertical tubular housing 36 through which the pump shaft 35 projects. The housing 36 has an inturned flange 36a at the top end thereof. A graphitic carbon bearing ring 37 is seated in the housing 36 against this flange 36a. A pump liner 38 supports the bearing ring 37 and, in turn, is supported by a second bearing ring 39. This bearing ring 39 is bottomed by a ring plate 40 which is secured by means of cap screws such as 41 to the bottom end wall of the casing 36.

A pump rotor 42 is mounted in the casing 36 and receives the drive shaft 35 therethrough in pressed relation. The rotor 42 has hub portions 42a rotatably mounted in the bearing rings 37 and 39. Vanes 43 are slidably mounted in slots 42b of the rotor 42 and have outer end portions riding on the inner wall 38a of the liner which provides the eccentric pump bore.

The liner 38 has a plurality of inlet slots 38b aligned with an inlet opening 36b in the side wall of the casing 36 remote from the tubular portion 23.

The liner 38 has a plurality of similar slots 38c aligned with a passageway 23a provided by the tubular leg 23.

A cylindrical screen 44 is disposed around the casing 36 and covers the inlet opening 36b thereof. The screen 44 is supported on the plate 40.

A cylindrical collar or metal shield 45 is disposed around the screen 44 in spaced parallel relation therefrom and has a cut-out portion receiving the tubular leg 23 therethrough. The collar 45 is supported against the upstanding leg 19 of the unit and is held in fixed relationship around the screen to provide an annular open-ended vertical passageway 46 communicating at its top and bottom with the pump P.

As shown in Figure 1, the lower end of the collar 45 has an outturned lip 45a providing a somewhat enlarged mouth at the bottom of the passageway 46.

The shaft 35 projects beyond the bottom of the casing 36 and a dished metal disk 47 is bolted on this extended end of the shaft. The disk 47 has an upstanding annular skirt 47a surrounding the lower end of the casing 36 and projecting upwardly into the passageway 46.

Propeller blades 47b project radially outward from the upper end of the skirt 47a. The propeller blades are pitched to cause agitation of liquid in the passageway P for excessively beating the liquid in the passageway to liberate bubbles B of vapors and gas therefrom. These bubbles rise through the passageway 46 and through the pond P to burst at the surface of the pond for discharging their gases and vapors from the liquid.

In operation, the unit 12 is submerged in the pond P of the tank and, of course, the passageway 46 thereof is filled with liquid since it is in free communication with the pond at both the top and bottom ends thereof.

The motor 28 drives the motor shaft 30 for driving the pump shaft 35. This pump shaft

carries the agitator 47 at the lower end thereof and the propeller blades 47b act on liquid in the passageway 46 to beat out the gases and vapors therefrom for liberating the bubbles B. The pump shaft 35 also drives the pump rotor 42 and the vanes 43 act on the bore 38a of the liner 38 to positively propel liquid from the inlet 36b of the casing through the passageway 23a of the tubular member 23. This passageway 23a communicates with a vertical passageway 19a in the upstanding tubular leg 19. Liquid is thus pressured into the passageway 19a and flows therefrom through the conduit nipple 21 into the fuel line of the airplane.

The bubbles B in the passageway 46 cannot pass through the screen 44 since they are larger than the screen mesh. However, these bubbles are free to rise through the passageway so that the passageway does not become gas-bound.

From the above descriptions it will be understood that the pump of this invention vigorously agitates and churns fuel in a localized open-ended passageway provided around the pump in a pond of the fuel in which the pump is mounted. The thus agitated and churned liquid has bubbles of gases and vapors separated therefrom. These bubbles are too large to pass through a screen which covers the inlet of the vane-type pump. The vane type pump thus only receives bubble-free liquid and propels this liquid under positive pressure to the fuel line leading from the tank.

The pump of this invention will thus prevent vapor lock in airplane fuel systems since even though the fuel is at or very close to its boiling point in rarefied high altitude atmospheres, any of the fuel which passes through the annular gap or passageway between the collar 45 and the screen 44 will be agitated by the blades 47b to beat out the bubbles B of vapor and gas from the liquid. The blades 47b of the propeller are preferably adjusted at angles which will actually impel the fuel upwardly through the passageway 46 to aid in sweeping bubbles out of the passageway. The vane pump therefore receives degassed fuel from an upwardly flowing stream.

It will, of course, be understood that various details of construction may be varied through a wide range without departing from the principles of this invention and it is, therefore, not the purpose to limit the patent granted hereon otherwise than necessitated by the scope of the appended claims.

I claim as my invention:

55. 1. In combination, a rotary vane pump having an inlet and an outlet, a screen covering the inlet of said pump, and an agitator adjacent said inlet acting on material about to enter the inlet for beating out bubbles of gas and vapor therefrom, said screen having a mesh fine enough to prevent passage of the liberated bubbles therethrough.

60. 2. A vapor separating and pumping device which comprises a unit adapted to be submerged in a pond of liquid to be pumped, a pump associated with said unit having an inlet communicating with said pond, a screen covering said inlet, and an agitator associated with said unit acting on liquid in the pond about to enter the inlet of the pump for beating out bubbles of gas and vapor therefrom, said screen having a mesh sufficiently fine to retard passage of the liberated bubbles therethrough.

65. 3. A vapor separator and pump assembly comprising a pump having a screened inlet, means

defining an open-ended passageway along said screened inlet, and a propeller in said passageway arranged for flowing liquid through the passageway and agitating the liquid to beat out bubbles of gas and vapor therefrom larger than the meshes of the screen whereby liquid entering the pump is degasified.

4. A pump and motor unit comprising vertically spaced pump and motor casings, a positive displacement pump in said pump casing, a motor in said motor casing having a shaft driving said pump, a mounting base for securing the unit in submerged position in a tank, a shield surrounding the motor casing defining an open-ended vertical passageway between the casing and shield, said pump casing having an opening between the ends of the passageway providing a pump inlet, and an agitating propeller driven by the motor shaft having vanes in the lower end of the passageway arranged for beating out bubbles of gas and vapor from liquid and for flowing bubble-rich liquid upwardly through the passageway.

5. In combination, a tank, a pump in the tank, a shield in the tank surrounding the pump in spaced relation defining an open-ended vertical passage in the tank, said pump having an inlet communicating with the passage, and an agitating propeller in the lower end of the passage

arranged to propel liquids upwardly through the passage and beat out bubbles therefrom to degasify the liquids before they are pumped.

6. In combination, a pump arranged for submersion in a pond of liquid, a shield surrounding said pump in spaced relation and defining a fluid flow path around the pump, said pump having an inlet opening communicating with said fluid flow path, and a propeller in said fluid flow path arranged for flowing liquid through the path and agitating the liquid to beat out bubbles of gas and vapor therefrom for feeding fully liquid material from said pond to said inlet of the pump.

15 7. A pump and motor assembly comprising a unit having a vane type pump, an electric motor drivingly connected with the pump, a propeller drivingly connected with the motor, and means for mounting the pump in a tank, a collar surrounding said pump receiving said propeller therein and defining the outer wall of an open ended annular passage around the pump, and said pump having an inlet communicating with said passage for receiving fully liquid material therefrom, said propeller being effective to flow liquid through the flow path and to agitate the liquid for releasing bubbles of gas and vapor therefrom.
